UNITED STATES PATENT OFFICE.

HENRY B. RENWICK, OF NEW YORK, N. Y., ASSIGNOR TO THE NATIONAL CASH REGISTER COMPANY, OF DAYTON, OHIO.

CASH REGISTER AND INDICATOR.

SPECIFICATION forming part of Letters Patent No. 440,116, dated November 4, 1890.

Application filed April 16, 1890. Serial No. 348,193. (No model.)

To all whom it may concern:

Be it known that I, HENRY B. RENWICK, a citizen of the United States, residing in the city of New York, in the State of New York, have invented a certain new and useful Improvement in Cash Registers and Indicators, of which the following is a description, reference being had to the accompanying drawings, forming part of this specification.

10 My invention relates to the indicating mechanism of such machines, and its object is to simplify and cheapen the construction thereof.

15 In the accompanying drawings I have illustrated my invention as applied to one of the usual well-known styles of these machines.

Figure 1 represents a side elevation of such machine, partly in section; and Figs. 2 and 3 show enlarged details of the supporting-bar 20 and indicator-rods.

The operating parts of the machine are supported in a frame-work consisting of the two side frames A A, connected and braced by suitable cross bars or rods, and are to be 25 inclosed in the usual case or cabinet, (not shown,) having a slotted front portion through which the forward ends of the operating-keys project, and a glass-covered reading-opening in its upper rear portion, through which the 30 indicators are exposed to view. The operating-keys B are pivoted on a shaft C at the front of the machine, and their projecting ends are provided with the usual numbered finger-buttons D. The rear ends of the keys 35 normally rest on a cross-piece E, connecting the side frames A A, and when the keys are operated play up and down in slots in a guide-plate F. Resting one on the rear end of each of the keys B are the tablet-rods or 40 indicator-supports G, free to move up and down in suitable guides H H', and provided at their upper ends with indicators or tablets I, bearing numbers corresponding to those on the finger-buttons D. Each of the rods G 45 has on its rear side a cam or wedge J, having an inclined upper surface and terminating in an abrupt shoulder at its lower end. These cams J co-operate with a supporting-bar K, which extends across the entire series of rods, 50 and is hung at its ends by ears or side arms L on pivots M, projecting from the side frames

A A. Its own gravity causes it to normally rest in the position shown in Fig. 1, against a pin N, projecting from the side frame A, though a spring may be employed to yieldingly hold it in that position, if desired. The front side of the bar K has two projections—one X, upon which the rods rest when up; the other O, against which the cams of the rods 55 strike in rising, so as to completely disengage any rod resting upon X.

As the finger-button D of any key is depressed, the corresponding rod G is lifted, and as its beveled cam or wedge J strikes the lower edge of the bar K the latter is pushed 60 backward, and still farther backward when the cam strikes the projection O. As the rod descends the bar falls back to the position shown in Fig. 1, and catches the cam on the projection X, as seen in Fig. 2, and thereby 65 holds the rod and table elevated when the operating-key is released and falls back to normal position. When the finger-button of another key is now depressed and its rod G is thereby lifted, the cam J on the latter will 70 engage the lower edge of the bar K and push it backward, as did the projection on the previously-elevated rod. Just as the cam on the second rod clears the projection X, the cams on the two rods will be in line with each other, 75 and if the parts were all constructed with the utmost accuracy and the adjustment were perfect the cam on the first-lifted rod would be released from the bar, and the rod and its tablet would drop back to normal position; 80 but it has been found, from practical use of these machines, that the release of the elevated rod in this manner cannot be depended on, for if there be the slightest wear or accumulation of dirt, or the parts be not constructed with the greatest accuracy and most delicately adjusted, the rising rod will often 85 fail to release the previously-elevated one.

To insure the release of the first-lifted rod by the lifting of the second, I so adjust the 90 parts that the full stroke of a key not only lifts its rod until its cam passes the lower engaging and supporting portion X of the bar K, but moves it a farther distance to cause its cam to strike against the releasing projection O of the bar, which is at a point some 95 distance above the supporting projection X,

and thereby push the bar farther to the rear than it was moved by the passage of the cam over its lower edge or projection O, as will be clearly seen in Fig. 3.

- 5 In Figs. 2 and 3 the dotted lines represent the vertical lines in which the extreme rear points of the cams J move, so it will be seen that when the bar K is moved to the position shown in Fig. 3 it will be certain to release 10 any cam which may have been resting on it. As the operated key is released and its rear end drops back to normal position, the cam on its rod, as the latter begins to descend, is caught on the projection X of the bar and 15 held up, with its indicator exposed to view. Pins through the lower ends of the rods G limit the upward play of said rods by striking the guide-piece H'.
 Inasmuch as it is absolutely essential to the 20 proper operation of machines of this class that the indicator, which is exposed to view, shall always be dropped out of sight when a second key is operated and another indicator lifted into view, various means have heretofore been devised for the purpose of giving the supporting-bar a further movement than could be given it by the mere passage of the cam on the rising-rod, that most generally employed being a train of independent mechanism interposed between the keys and the supporting-bar.

My invention by simply providing the supporting-bar with both a supporting portion and a releasing portion, both acted on by the 25 cam on a rising tablet-rod in the manner described, does away with the necessity for any of the independent or auxiliary devices heretofore employed, and simplifies and cheapens the construction of the indicating mechanism 30 of these machines. So far as I am aware, I am the first to produce an indicator-supporting bar of any sort, which is provided with both a supporting portion and a releasing portion, co-operating with a series of cams 35 formed upon indicator rods or supports in the manner described, and my invention therefore is not limited to any particular form or relative arrangement of the bar and the cams on the rods, so long as they operate to support and release the rods, substantially as hereinbefore described.

The bar K, instead of swinging on pivots,

may be arranged in guides, so that when actuated upon by the cams it will slide bodily away from the row of rods, instead of swinging in the arc of a circle. Again, the cams may be formed on the sides of the rods instead of the rears thereof, and there may be substituted for the swinging bar its known equivalent, a bar extending the whole length 60 of the row of rods and sliding in the direction of the length of the row, said bar being provided with a series of projections passing between the rods, one for each rod, and each projection having an acting face, substantially like that of the bar K, (shown in the drawings,) a spring or weight being employed to yieldingly force the projections on the bar toward the cams on the rods, this modification being in fact a mere change of position 70 of the cams with reference to the row of rods, accompanied with a corresponding change of direction of motion of the supporting-bar, as will be readily understood.

Inasmuch as my invention has to do with 75 only the indicating mechanism of these machines, the mechanism for registering or recording the values of the operated keys may be of any usual or suitable character, that illustrated in the drawings consisting of two 80 banks P Q of individual registering-wheels carried on horizontal shafts supported in a supplemental frame R, carried by the side frames A A. The wheels of the lower bank are actuated by the weighted dogs S, pivoted 85 to the keys B, and the wheels of the upper bank are turned by and register the revolutions of those in the lower bank in the well-known manner.

Having thus fully described my invention, 90 I claim—

In a cash-indicator, the combination of a bar provided with both supporting and releasing portions, with a series of indicator-supports or tablet-rods provided with a single set of cams co-operating with both the supporting and releasing portions of said bar, substantially in the manner and for the purpose specified.

HENRY B. RENWICK.
